UNITED STATES PATENT OFFICE.

JOHN W. DOTY, OF BROOKLYN, NEW YORK, ASSIGNOR TO THE FOUNDATION COMPANY, A CORPORATION OF NEW YORK.

CAISSENS AND METHOD OF JOINING THEM.

1,068,228.

Specification of Letters Patent. Patented July 22, 1913.

Application filed March 22, 1913. Serial No. 756,264.

To all whom it may concern:

Be it known that I, JOHN W. Doty, a citizen of the United States, residing in the borough of Brooklyn, county of Kings, and 5 State of New York, have invented new and useful Improvements in Caissons and Methods of Joining Them, of which the following is a specification.

This invention aims to provide certain improvements in the sinking of caissons or piers for building foundations and the like, which piers are sunk alongside of each other and then connected together so as to form 10 a continuous structure which will prevent the passage of water and earth between the piers when an excavation is made at one side of the same. The two piers are sunk with a slight space between them after which 15 vertical diaphragms are provided inclosing at least a portion of said space. The inclosed portion of the space is then excavated and is filled with concrete which is keyed into the joint faces of the piers. The vertical diaphragms are also preferably keyed 20 into the piers. For forming the diaphragms at least one, and preferably both of the piers, is sunk with closed vertical grooves in their joint faces and after sinking this groove is gradually opened from the bottom 25 upward while concrete or other plastic material is simultaneously forced down through the grooves and across the space between the piers. This operation being gradually continued from the bottom upward completes 30 the diaphragm to the height desired; and such a diaphragm alone may be used in some cases as the entire means for preventing the 35 passage of water or earth between the piers.

The accompanying drawings illustrate an 40 embodiment of the invention.

Figure 1 is a horizontal section of the adjacent portion of two piers; Fig. 2 is a vertical section on the plane 2—2 of Fig. 1; Fig. 3 is a vertical section on the plane of 45 3—3 of Fig. 1; Fig. 4 is a section similar to Fig. 3 after the work of constructing the diaphragm has been commenced; Fig. 5 is a section similar to Fig. 1 after the completion of the joint; Fig. 6 is a horizontal section on the line 6—6 of Fig. 2 after the completion of the joint.

In the construction illustrated the caisson

is formed of concrete so that it constitutes in fact the thick shell of the pier itself. Two such piers A are 55 illustrated with their adjacent joint faces slightly separated from each other to provide a space B across which the joint is to be made. Near each of the edges of the joint face the pier is formed with a vertical 60 groove C which is closed by means of a built-up channel composed of a plate D and angles E. The groove is formed of vertical timbers F and G on opposite sides and H at the back all fastened by bolts to angles J 65 extending from front to rear of the pier and located at suitable intervals to hold the timbers. The grooves C extend clear to the cutting edge K, being tapered at the lower end as shown in Fig. 3, and the plate D 70 being extended downward so as to overlap a part of the cutting edge. The angles J are braced at their ends by means of triangular braces L, the members J and L being both embedded in the concrete. 75

The built-up channel by which the grooves are closed fits in the grooves so loosely as to permit its withdrawal, but not to permit the entry of earth into the grooves.

After sinking the piers to bed rock or 80 other suitable substratum they will appear as in Fig. 1 with their grooves C opposite each other. Although the piers are not sunk perfectly straight, and the opposite grooves C will not always register exactly as 85 shown, yet they are made of substantial width and they will always register sufficiently closely for the contemplated method of operation. Concrete is deposited in the grooves C through their upper ends. Or in 90 some cases packed clay may be used for the same purpose. It is then rammed and simultaneously the plates D and angles E are gradually lifted as indicated in Fig. 4. The concrete M under pressure displaces the material between the two opposing grooves and forms a bond or vertical diaphragm N between the two caissons. This is continued to the top, or to as high a point as is desired for the diaphragm. The diaphragm will be 100 keyed into the opposite piers as indicated in Figs. 5 and 6. Two of these diaphragms N are preferably formed, as indicated in Fig. 5. The portion of the space between the

piers A which is bounded by these diaphragms is entirely inclosed and may be excavated from the top either by putting an air lock where the circumstances require it or without such an air lock. Upon removal of the earth from this portion of the joint the earth is replaced with a body of concrete O. This with the diaphragms N forms a body of concrete extending nearly from edge to edge of the piers and practically filling the space between them.

The body of concrete O is also preferably keyed into the faces of the opposite piers as indicated in Fig. 5. This is accomplished by forming wide vertical grooves P (Figs. 1 and 2) in which is a boxing of timber fastened at intervals to the transverse angles J and serving to prevent the entry of earth into the groove during the sinking operation (which entry of earth would be attended with danger to any nearby buildings supported on shallow foundations). After sinking the pier the closing plate Q and its stiffening rib R and the transverse members S, which are arranged at intervals in the grooves, are removed so that the body O of concrete shall enter the grooves and make a good joint between the piers. The large groove P extends downward only to a point above the level of the roof T of the working chamber of the caisson, because at this point the wall of the caisson or pier A is made thinner and it would not be practical to form a very deep groove in the outer face of such wall. Below the bottom of the groove P, however, there may be formed in the outer face of the working chamber shallow small grooves U (Figs. 2 and 6) which during the sinking operation may be filled with clay or may even be left open, being of such slight area as not to provide very much space for the earth to fall into. After the diaphragms N are formed the central excavation will not only involve the removal of the outer closing members Q, R and S of the larger grooves P, but will involve also the excavation of the clay or earth from the smaller grooves U so that the body O of concrete will extend into these smaller grooves clear down to the cutting edge.

Though I have described with great particularity of detail certain specific processes and constructions embodying the invention yet it must not be understood therefrom that the invention is restricted to the particular methods and constructions described. Various modifications in the steps of the process and in the details and arrangements of the construction described may be made by those skilled in the art without departure from the invention.

What I claim is—

1. The method of making a joint between piers which consists in sinking the two piers

with a slight space between them, forming 65 vertical diaphragms inclosing a portion of said space, excavating such inclosed portion and filling the excavated space with concrete.

2. The method of making a joint between 70 piers which consists in sinking the two piers with a slight space between them, forming vertical diaphragms inclosing a portion of said space, excavating such inclosed portion and filling the excavated space with concrete and 75 keying the same into said piers.

3. The method of making a joint between piers which consists in sinking the two piers with a slight space between them, forming 80 vertical diaphragms keyed into said piers and inclosing a portion of said space, excavating such inclosed portion and filling the excavated space with concrete.

4. The method of making a joint between piers which consists in sinking the two piers 85 with a slight space between them, forming vertical diaphragms keyed into said piers and inclosing a portion of said space, excavating such inclosed portion and filling the excavated space with concrete and keying 90 the same into said piers.

5. The method of making a joint between piers which consists in sinking the two piers with a slight space between them and with a closed vertical groove in the joint face 95 of at least one of said piers and extending clear to the top thereof, and subsequently opening said groove and forming a structure across such space and keyed into said groove.

6. The method of making a joint between piers which consists in sinking the two piers with a slight space between them, at least 105 one of said piers having a closed vertical groove in its joint face, opening said groove gradually from the bottom upward and simultaneously forcing plastic material down through said groove and across said space to form a vertical diaphragm.

7. In the making of a joint between piers 110 the method which consists in providing uncovered grooves in the side walls of the working chamber of such piers, sinking two piers with such grooves in their adjacent side faces, excavating the space between said adjacent faces and removing any clay or earth in said grooves, and filling the excavated space and said grooves with concrete.

8. A joint caisson formed with a vertical groove in its joint face, means for closing 120 said groove during sinking, said means being removable after sinking to open the groove.

9. A joint caisson formed with a vertical groove in its joint face, means for closing 125 said groove during sinking, said means being adapted to be removed gradually from the bottom upward after sinking to open the

groove and permit the forming of a dia-
phragm across the space between said cais-
son and the adjacent one.

10. A joint caisson formed with an open
groove in the joint face of the working
chamber.

In witness whereof, I have hereunto

signed my name in the presence of two sub-
scribing witnesses.
